HUMIDIFYING APPARATUS

Howard R. Oltz, Hammond, Ind.

Application April 14, 1947, Serial No. 741,314

1 Claim. (Cl. 236—44)

1

My invention relates to humidifying apparatus and in particular to a novel type of such apparatus which is adapted to be installed upon the conventional heating radiator in a manner so as to utilize the heating fluid or medium for humidification purposes.

In many prior art humidifying apparatus installations it is necessary to add to the ordinary heating system a complicated arrangement of valves, control circuits and connections to a water supply system to obtain the moisture necessary to maintain a desired humidity condition. With the apparatus of the present invention most of this equipment is unnecessary and a simple, inexpensive installation can be effected on a radiator either in a hot water system or in a steam system.

It is, therefore, the principal object of my invention to provide a simple, effective, efficient and inexpensive humidifying apparatus which utilizes either hot water or steam from the radiator to which the apparatus is attached for humidifying the air in a room or other space.

A second object is to provide an improved humidifying apparatus which is easily installed upon existing heating equipment.

Another object is to provide an improved humidifying apparatus which needs no extra water supply pipes or valves as was generally the case with the prior art humidifiers.

A further object is to provide an improved humidifying apparatus which is rapid in its response to the demands for humidification in the space being heated.

Still a further object is to provide an improved humidifying apparatus having a minimum number of parts which are simple in construction and are easily maintained in operating condition.

Other objects and advantages will become apparent from the following description taken in connection with the accompanying drawings, in which—

Fig. 1 is an elevational view of a conventional hot water radiator, showing my improved humidifying apparatus installed thereon;

Fig. 2 is a large scale medial longitudinal sectional view of the humidifier shown in Fig. 1 and may be considered as being taken generally along the line 2—2 of Fig. 3, looking in the direction of the arrows, and with some parts being shown in elevation;

Fig. 3 is a plan view of the apparatus shown in Fig. 2, with the cover removed, and may be considered as being taken along the line 3—3 of Fig. 2, looking in the direction of the arrows;

Fig. 4 is a typical simple wiring diagram of the

electrical connections which may be used with the apparatus of Figs. 1 to 3;

Fig. 5 is a medial longitudinal view similar to Fig. 2, showing a modified form of apparatus for use with a steam radiator;

Fig. 6 is a view similar to Fig. 5, showing another modified form of my humidifying apparatus for use with a steam radiator; and

Fig. 7 is a typical simple wiring diagram of the electrical connections which may be used in installing the apparatus of either Fig. 5 or Fig. 6.

Referring first to Figs. 1 to 4, my improved humidifying apparatus indicated generally by the reference character 10 is shown mounted on a conventional hot water radiator 12 having the usual hot water supply pipes connected to a central unit (not shown).

The humidifying apparatus 10 includes a casting or casing 14 forming a container 16 having a bottom wall 15 integral with a cylindrical side wall 17 and having an open top 18. The casting 14 is formed with a radial extension or nipple 20 adjacent the bottom wall 15 which is threaded at 22 so that it may be screwed into a tapped opening 24 in the radiator 12. The humidifier 10 is thus mounted on the radiator. The casting or casing 14 which forms the container may be made from any one of a number of suitable metals or, if desired, it can be molded from a plastic material. The choice of materials is not critical, and I do not desire to be limited to any particular material.

The container 16 is provided with an internal boss 26 adjacent the projection 20 and integral with the wall 17. The boss is drilled or bored vertically at 28, and a plug 30 closes the lower end of the bore 28. A cross bore 32 through the nipple 20 connects the bore 28 with the interior of the radiator 12. At its upper end the bore 28 communicates with a bore or port 34 of substantially smaller cross sectional area which is countersunk at 36 to form a valve seat. The bores 32, 28 and 34 form a passageway connecting the interior of the radiator 12 with the interior of the container 16.

A valve 38 is adapted to close the passageway and seat in the valve seat 36 when the level of the water in the container 16 is at a predetermined height. A float 40 biasing the valve 38 toward closed position is connected to the valve 38 by a lever arm 42 which is pivoted intermediate its ends on the pin 44. The pivot pin 44 is mounted in the upper end of a standard or post 46, which may be cast integrally with the container 16, and the pivot pin is retained

in place by a cotter pin 48. This construction is simple and permits the ready removal of the valve 38 and float 40 for any desired cleaning of the container 16.

An electrical heating element 50 of cylindrical shape and of conventional construction is placed in the bottom of the container 16 and is connected to the source of electric power through a cable 52. At one end the cable 52 has a plug 54 which is removably connected to a complementary socket (not shown) mounted in a boss 56 formed on the outer face of the bottom wall 15 of the container 16. The cable 52 comprises a pair of conductors 58 and 60.

The conductor 58 is connected to one terminal of a humidostat or a humidity responsive device 62 which has its other terminal connected to one side 64 of a 110-115 volt source of alternating current or other suitable source of electric power. The conductor 60 is connected to one terminal of a switch 66 which has its second terminal connected to the other side 68 of the 110-115 volt line. The humidostat 62 is preferably of the type which incorporates a switch which will be closed if the humidity in the space being heated or in the space surrounding the humidostat falls below a predetermined relative value. This humidostat is also preferably of the type which may be set or regulated to be responsive to different relative humidities. The switch 66 is closed manually and if desired may be closed as an incident to the turning on of the radiator 12.

My improved humidifying apparatus operates in the following manner. The radiator is turned on and the switch 66 closed to condition the circuit for energization of the heating element 50. The container 16 is filled with water to approximately the level indicated in Fig. 2 by the water from the interior of the radiator. If the water in the container 16 initially is below or falls below the predetermined level, the float 40 descends (Fig. 2) raising the valve 38 from the valve seat 36 to open the outer end of the passageway connecting the interior of the radiator and the container 16. As the heating system is under a low pressure, the water flows from the radiator through the passageway and into the container 16 until the float 40 rises to close the valve 38.

The hot water from the radiator will evaporate from the container 16 at a relatively slow rate unless the heating element 50 has been energized. If the humidity in the room falls below the predetermined relative value the humidostat 62 closes the circuit to the element 50. This closed circuit is line 64, humidostat 62, line 58, connecting plug 54, heating element 50, connecting plug 54, line 60, switch 66 and line 68. The heating element will raise the temperature of the water in the container 16 and will boil it away. The steam driven into the room or space raises the relative humidity of the air therein.

As the water boils away the liquid level in the container 16 falls and the supply of water is replenished through the passage controlled by the valve 38. In this way relatively hot water is constantly supplied to the container 16 and is quickly converted into steam to be passed into the room to raise the relative humidity. Since the moisture used for the purpose of raising the humidity is steam, it assists in heating the space or room, and no heat losses are encountered in this apparatus. A screen cover 70 of a non-rusting material such as copper is

placed over the container opening 18 to prevent the splattering of hot water from the container 16 while the water is being boiled away by the heating element 50.

5 Should the radiator be turned off, it is advisable that the circuit to the heating element 50 be broken by opening the switch 66 so that the heating element will not be inadvertently energized by the humidostat 62 to boil away all of the water in the container 16 and thereby possibly burn out the element 50.

In Figs. 5, 6 and 7, I have shown modifications of the apparatus for use in connection with a steam radiator. Fig. 5 illustrates my humidifying apparatus mounted on a steam radiator 72 by means of an elbow fitting 74 having a fluid passage therethrough and provided with external threads 76 at its upper end. A generally cylindrical housing 78 having complementary threads 80 is threaded onto the upper end of the elbow 74 and is provided with an internal shoulder 82 which locks a dividing wall 84 between the outer end 86 of the elbow 74 and housing 78. The wall 84 is formed with a circular shoulder 88 engaging the elbow 74 accurately to position the wall 84 and so that a substantially fluid-tight seal is made between the wall 84 and the elbow 74. The wall 84 has a central aperture or port 90 communicating with a tapered valve seat 92 in which is seated a normally closed valve 94 formed at the lower end of a plunger 96.

Spaced vertically from the wall 84 is a second wall or plate 98 which is centrally apertured and 35 is seated against a shoulder 100 formed in the cylindrical housing 78. The plate 98 cooperates with a similar plate 102 to form a support for a solenoid winding 104. Plates 98 and 102 are connected by a tube 106 which is peened or de-40 formed at its extremities to secure the winding 104, plates 102, 98 and tube 106 into a unit. The interior of the tube 106 forms a slideway or 45 guideway for the movable armature or plunger 96. The winding 104 is enclosed by a jacket 108 of an insulating and waterproofing material to insulate the winding from the other parts of the apparatus and to prevent any leakage of moisture into the coil. A suitable cap 110 is threaded onto the upper end of the cylindrical housing 78 and has an interior boss 112 pressing on the upper 50 side of the plate 102 to hold the solenoid winding securely in place in the housing with the plate or wall 98 seated firmly on the boss 100.

Suitable conductors 114 and 116 are connected to the solenoid winding or coil 104 and pass 55 through an opening 118 in the housing 78, being protected and insulated therefrom by an insulating ferrule 120.

The valve 94 is formed with a shoulder or seat 60 112, and a coil spring 113 is confined between the shoulder 112 and the lower end of the tube 106 to urge the valve 94 downwardly toward closed position.

The cylindrical wall of the housing 78 is provided with a plurality of radially and angularly disposed openings or slots 122 located between the shoulders 82 and 100 for the passage of steam through the housing and into the space to be humidified.

70 The conductor 114 is connected to one end of the solenoid winding 104 and to one terminal of a switch 124 similar to the switch 66. The other terminal of the switch 124 is connected to one pole of a battery or other suitable source of electric current 126 by a conductor 127. The con-

ductor 116 connects the other end of the solenoid winding 104 to one terminal of the humidostat 62, the other terminal of which is connected by a conductor 128 to the other pole of the battery 126. The humidostat 62 may be similar to that described with reference to the disclosure of Figs. 1 to 4. While I have shown a battery for the source of electrical power it is to be understood that any suitable source may be used.

The humidifying apparatus of Figs. 5 and 7 operates in the following manner: The radiator is turned on and the switch 124 is closed either independently or as an incident to the turning on of the radiator to condition the control circuit for the operation of the valve 94. The elbow 74 is in communication with the interior of the steam radiator 72 and is, therefore, filled with steam. The humidostat 62, responding to a lowered humidity condition in the space, closes the circuit to the solenoid winding 104; this circuit is battery 126, conductor 128, humidostat 62, conductor 116, solenoid winding 104, conductor 114, switch 124, conductor 127 and battery 126. When the solenoid winding 104 is energized it moves the armature 96 upwardly against the pressure exerted by the spring 113, thereby moving the valve 94 away from the valve seat 92. The interior of the radiator 72 is in communication with the room being heated through the elbow 74, port 90, housing 78 and slots 122. Steam, therefore, passes from the interior of the radiator under the operating pressure of the heating system into the room, thereby raising the relative humidity of the air or atmosphere. When the relative humidity has been raised to the desired predetermined level the humidostat 62 breaks the circuit to the coil 104 and the spring 113 immediately shuts the valve 94. The spring 113 is of sufficient strength to overcome the small amount of pressure which is exerted against the valve 94 by the steam entering the housing 78 through the port 90.

The apparatus shown in Fig. 6 is a modification of that shown in Fig. 5 and similar reference characters indicate similar parts. In the apparatus of Fig. 6 an elbow 130 is connected to a radiator 72 and is threaded externally at 132 adjacent its upper end. Spaced downwardly from its upper edge 134 and adjacent the bend, the elbow is formed with an integral dividing wall 136 corresponding to the wall 84. Upstanding from the wall 136 is a cylindrical wall 138 which forms the housing which was formed by the wall 78 in the modification of Fig. 5. The dividing wall 136 is provided with a central port 140 communicating with a valve seat 142 which cooperates with a normally closed valve 144. The valve 144 has a valve stem 146 provided with a threaded bore 148 at its upper end.

The solenoid winding 104 is confined between the pair of plates 102 and 98 joined by the hollow tube 106 which forms the guideway for an armature 150. At its lower end the armature 150 has an integral screw part 152 which is threaded into the bore 148. A corrugated flexible diaphragm 154 having a central aperture 156 is confined between the shoulders provided by the armature 150 and the valve stem 146. At its periphery 158 the corrugated diaphragm is flat and is confined between the upper face 134 of the wall 138 and an internal shoulder 160 formed in a cap 162 and a cylindrical flange 164 of the plate 98. The diaphragm 154 is flexed to bias the valve stem

146 downwardly to maintain the valve 144 in normally closed position.

The cap 162 has an internal thread 166 which cooperates with the threads 132 on the upper end 5 of the elbow 130. The cap 162 is substantially deeper than the cap 110 of the embodiment shown in Fig. 5 and houses the solenoid coil 104; it is provided with the internal boss 112 to position the winding 104 in the apparatus. It also has an opening 168 through which the conductors 116 and 114 pass.

The steam passes from the interior of the housing formed by the wall 138 through suitable radially and angularly disposed openings or slots 170.

The apparatus of Fig. 6 operates in substantially the same manner as that in Fig. 5 and the control circuit illustrated in Fig. 7 may be used, the only difference being that the flexible dia- 20 phragm biases the valve toward closed position.

It will be appreciated from the foregoing de- 25 scription that I have invented a simple and highly efficient humidifying apparatus which attains all of the stated objectives claimed for it. It is also clear that it is rapid and positive in its operation.

While I have illustrated three modifications of my invention and two different control circuits, it will be apparent to those skilled in the heating 30 and ventilating art that changes and further modifications can be made in my improved humidifying apparatus without departing from the spirit and scope of my invention. Therefore, I desire to be limited only by the appended claim.

What I claim as new and desire to secure by United States Letters Patent is:

A humidifying apparatus for use with a radiator of the hot water type comprising a container, means for mounting said container on the radiator, a passage extending through said mounting means and connecting the interior of the radiator with the interior of said container so that the radiator supplies the water for humidification, the outlet from said passageway being adjacent the top of said container, a valve controlling the flow of water from the radiator, float means operatively connected to said valve for opening or closing said valve, an electric heating element in said container for accelerat- 45 ing the rate of evaporation of the water therefrom, said heating element being located at the bottom of said container so as to be entirely below the level of the water therein, a humidostat responsive to the humidity conditions in the surrounding atmosphere, an electric circuit includ- 50 ing said humidostat for energizing said heating element, and terminal means in the bottom of said container for connecting said heating ele- 55 ment into said electric circuit.
